DYNAMOELECTRIC MACHINE END FRAME

Stanley E. Tomkinson, Fort Wayne, Ind., assignor to
General Electric Company, a corporation of New
York

Filed Oct. 11, 1967, Ser. No. 8,957

Term of patent 14 years
The portion of the term of the patent subsequent
to February 20, 1982, has been disclaimed

Int. Cl. D13—02
U.S. Cl. D26—5

FIG. 1

FIG. 2

FIGURE 1

FIGURE 4

FIGURE 1 is a perspective view of an end frame for a dynamoelectric machine embodying the new design;

FIGURE 2 is a plan view of the end frame as seen from the bottom of FIGURE 1;

FIGURE 3 is an end view of the end frame of FIGURE 1;

FIGURE 4 is a plan view of the end frame as seen from the top of FIGURE 3; and

FIGURE 5 is a side elevational view of the end frame as seen from the left of FIGURE 3.

I claim:

The ornamental design for a dynamoelectric machine end frame, as substantially shown and described.
